UNITED STATES PATENT OFFICE.

GEORGE E. MARCOTTE, OF CHICAGO, ILLINOIS.

AUTOMATIC WEATHER STRIPPING.

Application filed June 13, 1922. Serial No. 567,956.

To all whom it may concern:

Be it known that I, GEORGE E. MARCOTTE, a citizen of the United States, residing at Chicago, in the county of Cook and State 5 of Illinois, have invented a new and useful Automatic Weather Stripping, of which the following is a specification.

My invention relates to improvements in automatic threshold or bottom door stop in 10 which a movable stop is automatically operated by the movement of the door; and the objects of my improvements are first, to automatically close the aperture between a door and the floor; second, to eliminate the usual 15 wood threshold; third, to so construct the device that it can be applied to any door; fourth, to make a simple, cheap and durable device, and other objects to become apparent from the description to follow.

20 In dwellings it is desirable to have the doors fit snugly at the bottom and yet do away with the usual wood threshold, this is especially true of doors leading to the outside, and with the use of my invention this 25 desirable condition is effectually obtained without having any obstruction on the floor.

To apply my invention to a door the bottom edge of the door is provided with a suitable groove and the mechanism comprises a 30 shutter made movable toward and away from the floor and having suitable connections which will automatically raise the shutter up from the floor as the door is swung to an open position and will lower 35 the shutter to contact the floor when the door is swung to a closed position.

To describe my invention so that others versed in the art to which it pertains can make and use the same I have illustrated it 40 on the accompanying two sheets of drawings forming a part of this specification, and in which:

Figure 1, is a fragmentary perspective view of the lower corner of a door provided 45 with weatherstripping embodying my invention; Fig. 2, is a side elevation of the same; Fig. 3, is an edge view of the same; Fig. 4, is a sectional view taken on line 4—4 of Fig. 2; Fig. 5, is a sectional view taken on 50 line 5—5 of Fig. 3; Figs. 6, 7, 8, 9 and 10 are perspective views of disassembled parts of the mechanism shown in Fig. 5; Fig. 11, is a fragmentary side elevation of a door provided 55 with weatherstripping embodying a modified form of my invention; Fig. 12, is a sectional view taken on line 12—12 of Fig.

11 and Fig. 13, is a sectional view taken on line 13—13 of Fig. 12.

Similar reference characters refer to similar parts throughout the several views. 60

The lower edge of the door 14 is provided with a suitable groove 15 to accommodate the mechanism, which in Figs. 1 to 5 comprises the shutter 16 rigidly secured to the rod 17 pivoted at each end at the edges of 65 the door. The shutter extends the entire width of the door and is moved down and up by mechanism to be described, automatically when the door is swung shut and open. In Figs. 11 to 13 the shutter 18 is mounted to 70 slide vertically toward and away from the floor and is connected to mechanism to be described for automatically moving the same when the door is swung shut and open.

Referring to Figs. 1 to 10, one end of the 75 rod 17 has rigidly secured to it the small gear 19 which meshes with the large gear 20 mounted on a spirally threaded sleeve 21 which is held against rotation by means of its square end 22 extending into the square 80 pocket 23 formed in the casing 24 having the cover 25 and secured to the edge of the door by suitable screws. The sleeve 21 is screw threaded on the interior into which the threaded pin 26 is fitted tightly so it cannot 85 be turned without the aid of a screw-driver. A coiled expanding spring 27 is placed in the pocket 23 between the bottom of the pocket and the square end 22 of the sleeve 21 to normally press the end of the sleeve 90 against the cover 25. The pin 26 projects beyond the hinged edge of the door 14 and in operation as the door is closed the end of the pin 26 will come into contact with the jamb of the door and with the sleeve 21 be 95 pushed in against the tension of the spring 27, to the left as viewed in Fig. 5. Since the sleeve 21 is held against rotation the spiral thread on the sleeve 21 meshing with the spiral grooves in the large gear 20 will rotate the gears 20 and 19 in one direction or the other each time the sleeve 21 is moved in or out. The parts are so connected and arranged that as the pin 26 is moved in, the shutter 16 will be moved down against the 100 floor and as the sleeve 21 is moved out under pressure of spring 27, the shutter 16 is moved up away from the floor. Thus it is clear that the shutter 16 is moved down against the floor each time the door is closed and is lifted 105 from the floor as the door is opened. As seen in Figs. 3 and 4 the shutter 16 contacts

110

with the floor on an incline so that the tendency will be to slide over any roughness on the floor as the door is closed, and to change this incline to the opposite direction 5 as is necessary when the door swings to the opposite side, a sleeve 21 and a gear 20 having oppositely directed spiral threads to those shown, are substituted for the present sleeve and gear and the rod 17 is transferred 10 to the bearing hole 28 provided in the plate or cover 25.

In the modified form shown in Figs. 11, 12 and 13, the shutter or slide 18 is mounted to slide vertically in the frame 29 15 secured in the slot 15 provided in the lower edge of the door 14. To move the shutter 18 down and up it is provided with a plurality of vertical extensions 30 on its upper edge to which are pivotally connected the 20 long arms of bell crank levers 31 which are pivotally mounted at 32 to the frame 29. The short arms of the bell crank levers 31 are pivotally connected to a bar 33 provided at one end with a pin 34 extending 25 beyond the hinged edge of the door 14 so that as the door is closed the end of the pin 34 will engage the jamb of the door and be pushed in against the tension of the spring 35 and move the shutter 18 down 30 into contact with the floor. The spring 35 is so connected as to normally hold the bar 33 to the right as viewed in Figs. 11 and 13, and thus hold the shutter 18 in a raised position. The pin 34 is preferably screw- 35 threaded into the end of the bar 33 to vary its extending position beyond the edge of the door. The parts are so constructed and arranged that the shutter 18 will be moved down against the floor when the door 40 is closed and will be lifted from the floor when the door is opened.

Having thus fully described my invention what I claim as new and desire to secure by Letters Patent of the United States is:—

45 1. In an automatic weatherstripping for the lower edge of a door, a flat strip mounted to pivot on a rod at one edge, a gear secured to the pivotal rod of the strip, a second gear provided with a female spiral

thread held against axial movement and 50 free to rotate and operatively mounted on a sleeve provided with an external spiral thread and free to move axially and held against rotation, a spring to normally hold the sleeve in one position, a projection on 55 the sleeve to extend beyond the hinged edge of the door and a pivoted lever normally disposed on the hinge jamb of the door arranged to have one free end engage the edge of the door and the other free end 60 engage the said extending projection.

2. In an automatic weatherstripping for the lower edge of a door, a flat strip mounted to pivot on a rod at one edge, a gear secured to the pivotal rod of the strip, a second gear provided with a female spiral thread held against axial movement and 65 free to rotate and operatively mounted on a sleeve provided with an external spiral thread and free to move axially and held against rotation, a spring to normally hold the sleeve in one position and a projection on 70 the sleeve to extend beyond the hinged edge of the door arranged to engage a part on the door jamb when the door is closed whereby the sleeve is moved longitudinally and the flat strip is swung on its pivot.

3. In a door structure an automatic weatherstripping for the lower edge of the door, comprising a flat strip mounted on the lower edge of the door arranged to be moved down and up, means for moving said strip down and up comprising a projection extending beyond the hinged edge of the door and rigid with a longitudinally slidable element and a pivoted lever on the hinge door jamb arranged to have one end contact with the edge of the door proper and the other end engage the said extending projection.

90 In testimony whereof I have signed my name to this specification in presence of a subscribing witness this 28th day of May, 1922, at Chicago, Illinois.

GEORGE E. MARCOTTE.
